CLAIM

The ornamental design for a toothpaste bottle, as shown and described.

DESCRIPTION

FIG. 1 is an exploded front, right and top perspective view of a toothpaste bottle, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the toothpaste bottle that form no part of the claimed design.

1 Claim, 8 Drawing Sheets
